COMPOSITE FLOOR DIVIDING STRIP

Filed July 8, 1929

UNITED STATES PATENT OFFICE

PASQUALE GALASSI, OF NEW YORK, N. Y.

COMPOSITE FLOOR DIVIDING STRIP

Application filed July 8, 1929. Serial No. 376,808.

This invention relates to dividing strips for terrazzo and similar floors and more particularly refers to improvements in dividing strips of the type where two different metals are employed one for the upper section of the strip and one for the lower section, said sections being joined to each other along their inner edges.

Terrazzo, granolithic, stucco and similar floors usually comprise a lower or foundation bed made of concrete or cement or mortar or other suitable material, and an upper or finishing layer generally consisting of a mixture of marble chips and cement, by means of which a good durable surface may be obtained as well as pleasing designs and color effects of a practically unlimited variety.

The upper layer which is generally placed in position after the foundation layer has been allowed to harden to a sufficient degree of consistency, is generally divided into a number of panels or units in a predetermined arrangement, which are obtained by outlining the desired design by means of dividing strips placed on or through the foundation layer.

These bars are generally made of relatively soft metal such as brass for instance, the wearing qualities of which are approximately equal to those of the floor itself; and according to the nature of the floor and of the design to be produced, the dividing strips may be of various thicknesses and lengths.

Relatively thin strips may readily be obtained out of sheet metal, and are suitable for floors of moderate size; however, relatively large floors, or floors composed of relatively large units, call for strips having sufficient rigidity to withstand the lateral pressure of the material without bulging when the floor is laid. These heavier strips are also generally made out of sheet metal but brass being an expensive material their use materially increases the cost of the floor. At times the ornamental features are such as to require extra thick metallic strips showing through the material, and in these cases, the cost is still higher.

In order to keep the cost of the product within reasonable limits therefore, it is important to reduce as much as possible the quantity of material used for the portion of the strip which is showing through, this being done without however, impairing the usefulness and strength of the product.

In another patent application, entitled Bimetallic floor strip, filed simultaneously herewith, I have described and claimed dividing strips made of an upper and a lower section joined along their inner edges by means of rivets or equivalent means. I have found that the cost of both the material and labor going into the production of such strips may be reduced to a certain extent if other methods of connecting the two sections of the strip are employed.

The primary object of this invention is to provide a driving strip of the character specified, composed of an upper and a lower section, said two sections being joined to each other along their inner edges by welding or brazing or similar processes.

Another object of the invention is to provide a dividing strip of the character specified in which the two sections are made out of two different metals welded or brazed to each other along their inner edges.

A further object is to provide a bimetallic floor dividing strip composed of an upper and a lower section, welded or brazed to each other along their inner edges, one of said sections preferably the lower section being formed internally with anchoring means laterally projecting therefrom.

Other objects and advantages of the present invention will more fully appear as the description proceeds and will be set forth and claimed in the appended claims.

Various embodiments of my invention are illustrated in the accompanying drawings, in which:

Fig. 1 is a fragmentary view in perspective of a floor strip composed of an upper and a lower section of even thickness, said sections being joined to each other edge to edge;

Fig. 2 is a similar view of another strip in which the upper section is composed of an upper relatively thick portion and a rela-

tively thin rib portion depending therefrom, the lower edge of said rib portion being welded or brazed to the upper edge of the lower section;

5 Fig. 3 is a fragmentary view in perspective of a strip comprising an upper section of the same type as shown in Fig. 2, and a lower section having its upper edge portion overlapping the rib portion of the upper section, 10 said upper edge and rib portion being welded or brazed to each other;

Fig. 4 is a fragmentary view in perspective of a strip composed of two relatively thin sections having their inner edge portions 15 overlapping and joined to each other by means of welding or brazing;

Fig. 5 is a fragmentary view in perspective of a similar strip in which the edge of the lower section is bent to form a flange extending laterally of the strip;

20 Fig. 6 is a fragmentary view in perspective of an upper and a lower section, the inner edges of both sections being bent to form flanges extending laterally therefrom, said 25 flanges being joined to each other by means of welding or brazing;

Fig. 7 is a fragmentary view in perspective of a strip similar to that shown in Fig. 1 in which the lower section is provided with ears 30 or lugs bent therefrom in correspondence of the upper edge so as to form anchoring and 35 positioning means for the strip;

Fig. 8 is a fragmentary view in perspective of a strip similar to that of Fig. 5 in which 40 the lower section has its upper edge portion laterally off-set from the body thereof, so as to form a recess adapted to receive the lower edge of the upper section; and

Fig. 9 is a vertical cross section showing a 45 strip of the type shown in Fig. 7 in position at the same time illustrating the function of the anchoring and positioning means.

Referring to Fig. 1, it will be observed that the strip illustrated comprises an upper section 10 and a lower section 11, said two sections being substantially of the same thickness and being placed edge to edge. The lower section is preferably made of metal different from and cheaper than the metal 50 composing the upper section but the saving in the cost of material thus effected being in fact the main reason for adopting the construction shown.

The two sections are joined to each other 55 by some suitable welding or brazing process, preferably by spot welding as shown at 12.

One of said sections, preferably the lower section, is provided with anchoring means of any description such anchoring means being 60 preferably also useful as positioning means determining the depth at which the strip is to be placed.

Said anchoring means are represented by 65 ears 13, struck off the body of the lower section and bent to project laterally therefrom,

but it will be understood that any suitable type of anchoring means may be used.

In Fig. 2 the upper section 14 has a relatively thick top portion 15 and a relatively thin rib portion 16 depending therefrom, the 70 lower section 17 being also relatively thin and being placed edge to edge against rib portion 16 and being joined thereto by any suitable welding or brazing process, preferably by spot welding as shown at 18.

75 In Fig. 3 the upper portion 19 has a section similar to that of upper portion 14 of the strip just described, being composed of a relatively thick upper portion 20 and a relatively thin portion 21 depending therefrom. The lower section 22 however, instead of being placed edge to edge with rib portion 21, has its upper edge portion overlapping said rib, said upper edge portion being welded or brazed to said rib, this arrangement providing a strong and more positive connection.

80 In this strip the lower section is shown provided with a different type of anchoring means which are in the form of open top cup members 23, struck off and laterally off-set from the body of the lower section.

85 This type of anchoring means is generally to be preferred to that shown in Figs. 1 and 2, because the longitudinal continuity of the metal section is not destroyed, said section being strengthened rather than weakened by the cup members.

90 In Fig. 4 I illustrate another strip which is composed of a relatively thin upper section 24 and a relatively thin lower section 25, said sections having their inner edge portions overlapping as shown at 26, said overlapping portions being joined to each other by welding or brazing, preferably by spot welding as shown at 27.

95 In Fig. 5 I illustrate a strip of the same character composed of an upper section 28 and a lower section 29, the upper edge of said lower section being bent to form a laterally extending flange 30 which acts as an anchoring and positioning means for the strip, at the same time increasing its rigidity.

100 In Fig. 6, I illustrate a strip in which the lower section 31 is also formed with a laterally extending flange 32, the upper section 33 being similarly formed with a laterally extending flange 34, said two flanges being abutting face to face, and being welded or brazed to each other, for instance, being joined by spot welding as shown at 35.

105 While spot welding has been mentioned as being the preferred method of joining the two sections of the strip together, it is to be understood that the selection of the method to be followed is to be left open and to be determined according to the conditions surrounding each case.

110 For instance, the selection of the method to be followed is influenced by the nature of

the metals to be joined and by the relative sections of the two parts of which the strip is composed; so that while in certain cases spot welding may be a satisfactory means 5 joining the two sections of the strip, in other cases oxyacetylene welding may be preferable, and in other cases again an ordinary brazing process should be used.

For instance in Fig. 7, I illustrate a strip 10 composed of a relatively thin upper section 36 and a relatively thin lower section 37, placed against each other edge to edge, said two sections being welded or brazed along their entire length as shown at 38. A similar 15 procedure may be followed in joining the two sections of the strip shown in Fig. 8, where 39 is the upper section and 40 is the lower section, the inner edge portion of said lower section being offset laterally of the body 20 thereof as shown at 41, forming a recess within which may be placed the lower edge portion of the upper section; the upper edge of the lower section being bent laterally of the body of said section to form a flange 42, which 25 may act as anchoring and positioning means for the strip while at the same time increases its strength and rigidity.

The strip shown in Fig. 7 is illustrated in position in Fig. 9 where 43 designates the 30 lower layer or bed of the floor, laid on the floor foundation 44 and 45 designates the upper layer. It will be observed that the anchoring means represented by ears 46 defining the line of separation between the upper 35 and the lower layer and will therefore also act as positioning means for the strip.

In practice, the upper section of the strip will ordinarily be made of brass while the lower section will be made of steel, but occasionally other metals than brass may be used for the upper section, according to the decorative effects to be achieved.

Strips of designs different from those shown may be made without departing from 45 the inventive idea; the drawings will therefore be understood as being intended for illustrative purposes only and not in a limiting sense. I accordingly reserve the right to carry my invention into practice in all 50 those ways and manners which may enter, fairly, into the scope of the appended claims.

I claim:

1. A unitary divider strip for terrazzo floors or the like, comprising an upper and 55 a lower section, said two sections being composed of two different metals and being welded to each other along their inner edges.

2. A unitary divider strip for terrazzo floors or the like, comprising an upper and a 60 lower section, said two sections being composed of two different metals and being welded to each other along their inner edges, and anchoring means integral with and extending laterally of said lower section.

65 3. A unitary divider strip for terrazzo

floors or the like, comprising an upper and a lower section, said two sections being composed of two different metals and being welded to each other along their inner edges, said lower section being formed with anchoring 70 means extending laterally of its upper edge.

4. A divider strip for terrazzo or like floors, comprising upper and lower longitudinal sections, the lower section having at its 75 inner edge a single uninterrupted flange extending laterally of the body thereof on one side only, and a connection between said upper and lower sections securing said sections together to form a unitary strip.

5. A divider strip for terrazzo or like floors, comprising upper and lower longitudinal sections, the lower section consisting of a single-layer strip having at its inner edge a single uninterrupted flange extending laterally of the body thereof on one side only, 85 said flange acting as positioning and anchoring means for said strip, and a connection between said upper and lower sections securing said sections together to form a unitary strip.
